CLAIM

The ornamental design for a computer display with transitional skeletal structure image, as shown and described.

DESCRIPTION

FIG. 1 is a front view of a first image of skeletal structure displayed as a portion of an interface within an electronic medical record system for a computer display;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the moving image sequentially transitions between images shown in FIGS. 1–6. The process or period in which an image transitions to another forms no part of the claimed design.

The broken line showing of a portion of a computer display is included for the purpose of illustrating environmental structure and forms no part of the claimed design.

In a particular embodiment, FIG. 1, FIG. 2, FIG. 3, FIG. 4, FIG. 5, and FIG. 6 provide the aesthetic of motion when displayed in sequence. For example, as an interface within an electronic medical record system changes to display a second skeletal structure from a first skeletal structure, the interface can provide a motion aesthetic. In the exemplary embodiment of FIGS. 1 to 6, the interface of the electronic medical record system can provide an aesthetic transition from a regional skeletal structure, such as a foot, to a second sub-regional skeletal structure, such as a toe.
